UNITED STATES PATENT OFFICE.

JAMES A. HARGAN, OF CHESTER, PENNSYLVANIA.

SHIP'S DAVIT.

SPECIFICATION forming part of Letters Patent No. 443,318, dated December 23, 1890.

Application filed May 13, 1889. Serial No. 310,523. (No model.)

To all whom it may concern:

Be it known that I, JAMES A. HARGAN, a citizen of the United States, and a resident of Chester, Delaware county, Pennsylvania, have 5 invented certain Improvements in Ship's Davits, of which the following is a specification.

My invention relates to the construction of davits to be applied to the side of a vessel for launching the small boats.

10 The main object of my invention is to construct mechanism by which the boat can be swung from its blocks to a position at the side of the vessel and lowered evenly into the water by simply turning the cranks and operating clutching mechanism, as fully described hereinafter.

15 In the accompanying drawings, Figure 1 is a longitudinal view of my improved davit with the boat in position, showing a portion 20 of the deck and rail of the vessel. Fig. 2 is an end view of the device with the vessel in section. Fig. 3 is an enlarged sectional view on the line 1 2, Fig. 2. Fig. 4 is a detached view of the lower portion of the davit-crane. Fig. 5 is a longitudinal view of a modified 25 form of the device. Fig. 6 is an end view of the same with the vessel in section, and Fig. 7 is a transverse section on the line 3 4, Fig. 5. Fig. 8 is a modification of the davit-crane.

30 Referring to Figs. 1, 2, 3, and 4, A A are the davit-cranes pivoted at *a* to the frames B, secured in any suitable manner to the deck of the vessel. The cranes are in the present instance straight bars; but they may be of 35 different shapes, as circumstances require. To the lower arm of each crane is secured a segmental rack A', having teeth *a'*, which engage with a pinion *c* on a sleeve C, loose on a shaft D. The sleeve C is provided with a 40 disk *c'*, having on its rear side a series of slots *c*², as shown in Fig. 1, and in the bearing B is a slot *b*. The sleeve can be fixed to the bearing by simply placing a pin *b'* in one or the other of the slots *c*² and in the slots *b* 45 in the frame, when it is required to lower the boat, or, in place of the slots, orifices may be made in the disk *c'* and a pin inserted therein and into an orifice in the bearing B, as shown in Fig. 3. The shaft D extends from one 50 bearing B to the other, and has bearings therein, and is provided at each outer end with a gear-wheel D', which meshes with a

pinion *d* on a shaft D², provided with a crank-handle *d'*, by which it is turned, although in some cases short shafts D may be used 55 at each end, according to the location of the davit.

On the side of the gear-wheel D' on the shaft D is a band-wheel *s*, to which is applied a friction-band *s'*, connected to a foot-lever S, 60 on depressing which the band will be tightened upon the wheel, thus placing sufficient friction on the shaft D to hold it in any position required.

At each end of the shaft D is a clutch E, constructed as shown in Fig. 3, having two clutch portions *e* *e'*, the shanks of which are threaded, and adapted to these threaded shanks is a sleeve *e*², having a suitable wheel *e*³, by which it is turned. This sleeve *e*² is confined longitudinally to the shaft by a collar *e*⁴; but the shaft and collar *e*⁴ are free to turn in the sleeve *e*². By turning the sleeve *e*² in one direction by hand the clutch-face *e* will be thrown into gear with the clutch-face of the sleeve C, thereby imparting movement to the pinion *c* and davit-crane A; but if the clutch-sleeve is reversed the clutch-face *e* will be moved away from the clutch-face of the sleeve C, and the clutch-sleeve *e* will be thrown into gear with a clutch-face *f* on a drum F, around which is passed the rope or chain *x*, forming 70 part of the hoisting mechanism by which the boat is lowered into the water or raised therefrom, so that it will be seen that by turning 75 the crank-handles *d'* and moving the clutches into gear with one or other of the clutch-faces the davit-cranes will be moved or the hoisting-tackle will be operated. Each rope or chain is attached at one end to a cleat *x'* on 80 the vessel, and passes through pulley-blocks *y* *y'*, each pulley-block *y* being attached to the upper portion of each crane A, and the lower pulley-block is provided with a hook *y*², which is passed through a ring on the boat. 85

The shaft D is supported by intermediate bearings *d*², and by duplicating the operating mechanism two or more persons can operate the davit, or the davit can be operated at either end, as circumstances require. The 90 davit-cranes are connected together at their upper ends by spans *a*², and have guys *a*³ at each end, passing to points on the vessel. 95

As shown in Fig. 2, the davit mechanism is

so constructed that two boats can be placed side by side on the vessel and the davit swung so as to remove either of the boats without disturbing the other.

- 5 To remove the boats from the vessel—say, for instance, the boat W', Fig. 2—the davit is swung to the dotted line w' , and the hoisting-tackle is then attached to the rings on the boat and the boat is lifted so as to clear the boat W when it swings. When it is lifted to this position, the clutch is thrown in, so that on turning the handles d'' the cranes will swing to the position shown by the dotted line w' , Fig. 2, which would be sufficient for the boat 15 to clear the side of the vessel, the clutch being then reversed and the boat lowered into the water. The same is the case when lowering the boat W, except that in this case the hinged portions n of the cradle U are let 20 down, and the boat can be swung out to a position clear of the vessel without first lifting the same.

In Figs. 5, 6, and 7, instead of having the mechanism for turning the shaft D at each 25 end, I place this mechanism in the middle, and secure to the shaft a worm-wheel D^3 , which meshes with a worm D^4 on a shaft D^5 . This shaft is provided with a handle d^6 , which is supported at its outer end by a standard d^7 , both handle and standard being portable. The handle is of sufficient length to allow two or more men to turn the crank. The segment on the davit-crane in this instance is shorter than that shown in the former figures, and 35 only swings from the vertical position to the position shown by the dotted line w' .

In Figs. 5, 6, and 7 I have shown the mechanism simply adapted for turning the crane, the hoisting-rope being operated by independent mechanism, although it will be understood that the rope can be wound around the drum on the shaft, and the mechanism described with reference to Figs. 1 and 2 can be utilized in this connection.

- 45 The segment may be made, as shown in Fig. 8, above the pivot a of the crane.

I claim as my invention—

1. The combination of the swinging crane of a davit, a clutch-disk geared to said crane, 50 the boat hoisting and lowering mechanism, a clutch-disk connected thereto, a shaft, a

clutch thereon adapted to engage with either the clutch-disk of the davit-crane or the clutch-disk of the boat hoisting and lowering mechanism, substantially as specified.

55

2. The combination of the opposite frame B B, the davit-cranes A A, pivoted thereto, each having a segment-gear at its lower end, with a shaft D, having its bearings in both frames, pinions $c c$, meshing with the segment-gears, with a crane-shaft geared to said shaft D, whereby the davit-cranes can be moved, substantially as set forth.

60

3. The combination of the frame B, a davit-crane A, pivoted thereto, carrying a segment-gear at its lower end, a shaft D, a pinion c , meshing with the segment-gear, a gear-wheel on said shaft, a crank-shaft, and a pinion b , mounted thereon, substantially as described.

65

4. The combination of the driven shaft having thereon a clutch, with a drum adapted to engage with said clutch, and around which passes the rope or chain of the hoisting mechanism, a sleeve on said shaft adapted to engage with the clutch, a pinion on said sleeve gearing with a segmental rack on the davit-cranes, the clutch being so arranged that on moving it in one direction the davit-cranes will be thrown into gear and on moving it in the opposite direction the drum will be thrown 70 into gear, substantially as described.

70

5. The combination of the shaft, a hoisting-drum loose thereon, a loose sleeve carrying a pinion, said hoisting-drum being connected to the mechanism for raising the boat, and 75 the pinion geared to the segmental rack on the davit-cranes, with clutch-faces on the drum and pinion, with clutch portions $e e'$ on the clutch proper, having screw-threads on their shanks, and a screw-threaded sleeve engaging with said screw-threaded shank, so that on turning said sleeve one or other of the clutch-faces will be thrown into gear with either the pinion, sleeve, or drum, substantially as specified.

80

In testimony whereof I have signed my name to this specification in the presence of two subscribing witnesses.

JAMES A. HARGAN.
